(57) **CLAIM**

The ornamental design for a towel holder, as shown and described.

DESCRIPTION

1. Towel holder

This is a new design for a towel holder, a rack for holding towels or other items; FIG. 1.1 is a top, front, right side perspective view of a towel rack showing my new design; FIG. 1.2 is a top, rear, left side perspective view thereof; FIG. 1.3 is a front elevation view thereof; FIG. 1.4 is a rear elevation view thereof; FIG. 1.5 is left side elevation view thereof; FIG. 1.6 is right side elevation view thereof; FIG. 1.7 is a top plan view thereof; and FIG. 1.8 is a bottom plan view thereof.
